UNITED STATES PATENT OFFICE

EUGENE F. MARTINET, OF CLEVELAND, OHIO, ASSIGNOR TO THE P. A. GEIER COMPANY, OF CLEVELAND, OHIO, A CORPORATION OF OHIO

DESIGN FOR A SUCTION CLEANER HANDLE GRIP

Application filed April 10, 1931. Serial No. 39,428. Term of patent 14 years.

To all whom it may concern:

Be it known that I, EUGENE F. MARTINET, a citizen of the United States, residing at Cleveland, in the county of Cuyahoga and State of Ohio, have invented a new, original, and ornamental Design for Suction Cleaner Handle Grip, of which the following is a specification, reference being had to the accompanying drawings, forming part thereof.

Figure 1 is a perspective view of a suction cleaner handle grip showing my new design, Fig. 2 is a side elevation; Fig. 3 is a top plan view; and Fig. 4 is a sectional view on the line 4—4, of Fig. 3.

I claim:—

The ornamental design for a suction cleaner handle grip, as shown.

EUGENE F. MARTINET.
